ROBERT P. GREENLEAF, OF CLEVELAND, OHIO, ASSIGNOR TO FRANK BILLINGS, OF CLEVELAND, OHIO.

RAIL-CLAMP.

1,222,621.

Specification of Letters Patent. Patented Apr. 17, 1917.

Application filed September 3, 1914. Serial No. 320,004.

To all whom it may concern:

Be it known that I, ROBERT P. GREENLEAF, a citizen of the United States, residing at Cleveland, in the county of Cuyahoga and State of Ohio, have invented a certain new and useful Improvement in Rail-Clamps, of which the following is a full, clear, and exact description.

This invention relates to a rail clamp 10 adapted especially to serve as an anchor for certain types of machines, such as loading machines which are required to be held stationary on a track while in operation, and are adapted to be moved along the track 15 only when the machine is transferred from one working point to another or to advance a machine as the work progresses.

The object of the invention is to provide a clamp which is simple in construction and 20 can be easily clamped to a rail or released, and when clamped to the rail will effectively anchor or hold the machine against movement.

My invention will be briefly summarized 25 as consisting in certain novel details of construction and combinations and arrangements of parts which will be described in the specification and set forth in the appended claims.

30 In the drawing, Figure 1 is a side view of the rail clamp showing by dotted lines a wheel of the machine or vehicle which is to be anchored or held from movement in one direction by the clamp; Fig. 2 is an end view 35 of the same with the rail in section; and Fig. 3 is a top plan view with parts broken away and with the operating lever of the clamp shifted at right angles to the position shown in Figs. 1 and 2.

40 Referring now to the parts by reference characters, 10 represents a U-shaped clamp composed of two parts 10^a and 10^b which have upper inturned edges 10^c bearing against each other, and relatively short lower inturned edges 10^d between which there is an open space slightly less than the width of the ball of the rail. The sides of 45 the two members of the clamp constitute jaws which are adapted to engage the sides of the ball of the rail just above the lower inturned edges 10^d.

The upper corners of the clamping member 10 are preferably beveled, as shown at 50 10^e, these portions being adapted to be engaged by the wheel 11^a of the machine to be

anchored or held against movement. It may be here stated that two of these clamps or anchors will be utilized to hold the machine against movement in either direction, one being clamped to the rail in front of one of the front wheels, and the other being clamped to the rail in the rear of one of the rear wheels.

For the purpose of clamping the jaws to the rails or for releasing the same, I utilize 65 a clamping bolt 12 which extends transversely and loosely through the sides of the two members 10^a and 10^b at the transverse center plane of the latter. At one end of this bolt is an adjustable nut 12^a, and at its 70 opposite end is a flat head 12^b. The clamping and releasing means includes also a lever 13 having a bifurcated lower or inner end 13^a pivotally connected by a pin 14 to the head 12^b of the bolt. The bifurcated end 13^a 75 of the lever is provided with a cam lug or nose 13^b, which, when the lever is swung to a position at right angles to the bolt 12, or in parallelism with the sides of the clamp, causes the jaws or sides of the clamping 80 members to grip the rail, and when the lever is swung to a position at right angles to the sides releases the jaws from the rails.

Extending through the sides of the clamping members, near the side edges of 85 the same, and at a distance from the in-turned edges 10^d equal substantially to the thickness of the ball of the rail, are two pins which are fixed in one of the sides and extend loosely through the other. These pins 90 normally rest on the top of the rail, as shown in Figs. 1 and 2.

To apply the clamp to the rail the nut 12^a will be loosened sufficiently to permit the two members 10^a and 10^b of the clamp to be 95 moved apart or spread a sufficient distance to allow the clamp to be placed over the ball of the rail,—that is, with the rail between the clamping jaws, and with the pins 10^d resting on the top of the rail. If the nut is now moved inwardly to its normal position, the sides of the clamping member will still loosely engage the rail and the clamping action will not yet be had, thus admitting of the clamp being slid along the rail to or from clamping position against the wheel. To now tightly clamp the device to the rail, the lever 13 will be swung to a position parallel to the sides of the clamp, causing 105 the cam or nose 13^b to draw the jaws 110

tightly against the rail with enormous clamping pressure. It will be observed that the lever 13 may be swung either to vertical position, as shown in Figs. 1 and 2, or to horizontal position, as shown in Fig. 3 without effecting the clamping engagement between the jaws and the rail. This is of importance under certain conditions or with certain types of machine, for the character of the work or of the machine may not admit of the lever extending upwardly, in which case it can be swung horizontally and vice versa.

When the machine is to be advanced a short distance along the track, the lever will be swung to a position at right angles to the sides of the clamp, after which the clamp can be slid over the track the required distance, and after the machine has been properly positioned the clamp will be brought up against the wheel, and will thence be clamped to the rail by swinging the lever, as previously explained. If the machine is to be shifted a considerable distance along the track, the clamp is removed from the rail by first swinging the lever to releasing position, and then by loosening the nut 12^a until the slot between the edges of the clamping jaws is wider than the thickness of the ball of the rail.

This device is simple in construction, is easily applied to the rail and easily operated, and the clamping pressure is sufficiently great that the machine, in connection with which the clamps are utilized, will be held from movement regardless of the pulling or pushing stresses which tend to shift the machine along the track.

Having described my invention, I claim:

40 1. A rail clamp comprising a U-shaped member having clamping jaws and composed of two flat plates having at their upper edges inturned flanges which engage

each other and which are spaced from the rail when the jaws are clamped thereto, a 45 bolt passing loosely through the transverse center plane of said jaws, an adjustable nut on one end of said bolt, a clamping lever connected to the outer end of the bolt, said lever having a clamping cam for drawing 50 the jaws toward each other to produce a clamping action on the rail when the lever is swung to a certain position.

2. A rail clamp comprising a U-shaped member composed of two parts constituting 55 jaws adapted to clamp opposite sides of a rail, a clamping device extending through the same, a lever pivoted to the end of said device and adapted to be swung about its pivotal axis, said lever having means for 60 drawing the two parts toward each other to produce clamping action on the rail, and devices extending between said parts and located on opposite sides of said clamping device so as to rest upon the rail being 65 clamped.

3. A rail clamp comprising two jaws having a pair of pins extending from one member to the other and adapted to rest on the rail, a clamping bolt extending loosely 70 through the sides of said jaws between said pins, an adjustable nut at one end of said bolt, a clamping lever pivoted to the opposite end of the bolt, said lever adapted to be swung to and from a position of parallelism with the jaws, and said lever having a cam shaped nose adapted to engage one of the jaws to draw said jaws together and produce a clamping action.

In testimony whereof, I hereunto affix my 80 signature in the presence of two witnesses.

ROBERT P. GREENLEAF.
